Primary Examiner — Kendra Leslie Hamilton*(74) Attorney, Agent, or Firm* — Gottlieb, Rackman & Reisman, P.C.(57) **CLAIM**

The ornamental design for a container for litter, as shown and described.

DESCRIPTION

1. Container for litter

1.1 : is a top perspective view of a container for litter;

1.2 : is a bottom perspective view thereof;

1.3 : is a front elevation view thereof;

1.4 : is a rear elevation view thereof;

1.5 : is a left side elevation view thereof;

1.6 : is a right side elevation view thereof;

1.7 : is a top plan view thereof; and

1.8 : is a bottom plan view thereof.

The broken lines in the reproductions depict portions of the container for litter that form no part of the claimed design.

1 Claim, 8 Drawing Sheets(56)
